SANDBAG SUPPORT

Harry Schlesinger, Des Moines, Iowa, assignor of
one-half to Alfred F. Yoerg, Des Moines, Iowa

Application November 18, 1935, Serial No. 50,400

9 Claims. (Cl. 223—12)

An object of my present invention is to provide a sand bag structure for pressing hat brims, the structure being comparatively simple, and inexpensive from a manufacturing standpoint.

5 A further object is to provide a sand bag structure in which the heavy sand bag is raised by a spring or the like, the bag being lowered manually by a handle provided for that purpose and latched in the lowered position.

10 A further object is to provide a latch which, although there is a tendency for it to remain in latched position caused by friction produced by the means which raises the sand bag, can be readily released and to provide in connection with the latching means for the sand bag, a hydraulic check means so that the sand bag will not slam upwardly, thus producing excessive wear and a possibility of breaking parts of the device.

15 A further object is to provide a hydraulic check means so as to eliminate the necessity for the operator to hold the sand bag from moving upwardly too quickly.

20 A further object is to provide a device of the kind described in which a supporting post encloses a spring which counterbalances and raises the sand bag when the latch is released, a cylinder and plunger assembly being provided within the post and the post constituting a reservoir for oil for the cylinder and plunger, these parts forming a hydraulic check for the movement of the sand bag upwardly.

25 A further object is to provide in the hydraulic check, a check valve operable to permit quick entrance of oil to the cylinder when lowering the sand bag manually and a vent for permitting restricted flow only of oil out of the cylinder when the latch is released and the spring within the post raises the sand bag.

30 With these and other objects in view my invention consists in the construction, arrangement and combination of the various parts of my device, whereby the objects contemplated are attained, as hereinafter more fully set forth, pointed out in my claims and illustrated in the accompanying drawing, in which:

35 Figure 1 is a side elevation of a sand bag support embodying my invention.

40 Figure 2 is an enlarged sectional view on the line 2—2 of Figure 1 showing the post and internal details thereof.

45 Figure 3 is a sectional view on the line 3—3 of Figure 1 showing on an enlarged scale the latch lug and a latch pin latched together.

50 Figure 4 is a sectional view on the line 4—4 of Figure 3; and

Figure 5 is a view similar to Figure 4 showing the parts nearly latched.

I have used the reference numeral 10 on the accompanying drawing to indicate a base. The base 10 is forked to straddle a hat supporting block 12 and is provided with an upstanding boss 14 at one side thereof. The boss 14 is tubular and receives the lower end of a tubular post 16. The post 16 is held therein by a set screw 18. The post is shouldered at 20 (see Figure 2) to 5 limit its position with respect to the boss.

A collar 22 surrounds the post 16 and serves as a rest for a boss 24 of a supporting arm 26 of disc shape. The arm 26 has a boss 28 opposite the boss 24. A sand bag supporting shaft 30 is 10 vertically slidable in the boss 28. On the lower end of the shaft 30 I provide a spider 32 for supporting a sand bag casing 34. The bottom of the casing 34 is closed by a plurality of fire proof fabric covers 36 on top of which an electric heating element 38 is mounted. The space within the casing 34 above the cover 36 is filled with sand 40 in the usual manner.

A cover 36 is adapted for contacting with the brim 42 of a hat 44, which brim rests on a ring 46 of the proper size to fit the hat, the brim of which is being pressed. When the sand bag is in the lowered position, the weight of the sand causes equal conformation of the cover 36 to the hat brim throughout the entire area thereof.

25 A hub-like member 48 is secured as by a clamping bolt 50 to the shaft 30. This member is provided with a slot 52 receiving a pin 54 of an operating lever 56. The lever 56 is pivoted to the arm 26 at 58 and has a manipulating handle 60.

30 Opposite the handle 60 the end of the lever 56 is connected by a link 62 with a rod 64. The rod 64 extends slidably through a head 66 of the boss 24 and into the post 16. Its lower end is slidable in and guided by a cylinder 68. The rod constitutes a plunger in the cylinder.

35 I provide a spring 70 of sufficient strength to counterbalance the weight of the sand bag and raise it. The lower end of the spring is anchored to a flange 72 abutting against a shoulder 74 of the post 16. The upper end is anchored to a collar 76 secured as by a pin 78 to the rod 64.

40 The cylinder 68 is held stationary relative to the post 16 by a fitting 80 screwed into the lower end of the post below a suitable gasket 82. The fitting 80 is provided with a slot 84 for receiving a tool to screw the fitting into the post.

45 Within the fitting 80 a valve seat 86 is provided on which is normally seated a ball valve 88. A strainer screen 90 is provided interposed between 55

the fitting 80 and the space within the post 16 which space constitutes a reservoir for oil 92. Passageways 94 and 96 are provided in the flange 72 and the fitting 80 respectively, for permitting flow of oil. The fitting 80 is also provided with a vent 98, the purpose of which will hereinafter appear.

The hub-like member 48 is provided with a latch extension 100 having an inclined edge 102 and 10 latch notch 104. The boss 28 of the arm 26 journals or pivotally mounts a latch pin 106 having a latch notch 108. A bell crank lever 110 is secured to the pin 106 and is constrained to rotate to the position of Figure 4 by a spring 112. A suitable 15 stop may be provided to limit the clockwise rotation of the latch pin 106. In Figure 1 I show a stop pin 114 for this purpose.

Practical operation

20 In the operation of my sand bag support, the plunger 64 normally assumes the position shown by full lines in Figure 2 and the handle 60 is raised. When it is desired to use the sand bag to press a hat brim, the handle 60 is grasped and pulled downwardly, thereby lowering the sand bag and stretching the spring 70. The latch extension 100 will first assume the dotted position shown in Figure 5 and then upon further downward movement the incline 102 will rotate the 25 latch pin 106 against the action of the spring 112 to the full line position and finally when the notch 104 registers with the latch pin as shown in Figure 4 the spring 112 will swing the latch pin back to the position shown in Figure 4. The sand bag is now securely latched in position.

When it is desired to raise the sand bag to its upper position, it is merely necessary to swing the bell crank 110 counter-clockwise so that the bottom of the notch 108 will swing to a substantially 40 vertical position, which releases the extension 100 and permits the spring 70 to contract. The operation of swinging the latch pin 106 from the position of Figure 4 to the position of Figure 5 is comparatively easy because the circumference of the 45 pin 106, which constitutes a latching surface, is naturally on a radius from the pivotal axis of the pin. The spring, however, will not contract quickly because it must force the oil out of the cylinder 68 through the vent 98 which is quite 50 small and therefore permits the sand bag to move up slowly instead of quickly and eliminates the necessity of the operator having to retain the handle against quick upward movement.

When the handle is moved downwardly, however, the valve 88 lifts off the seat 86 and permits quick entry of the oil 92 to the cylinder 68, which is obviously desirable. The screen 90, aside from keeping dirt out of the check valve, serves to prevent air from being drawn into the cylinder and thus forming air pockets. The post 16 may be provided with an oil filler plug 116 into which oil can be introduced until it reaches the level of the plug.

Some changes may be made in the construction and arrangement of the parts of my device without departing from the real spirit and purpose of my invention and it is my intention to cover by my claims any modified forms of structure or use of mechanical equivalents which may 65 be reasonably included within their scope.

I claim as my invention:

1. In a sand bag support, a base, a post extending upwardly therefrom, a sand bag, a vertical shaft connected with said sand bag, said post supporting said shaft for sliding movement, a lever

pivoted to said post and to said vertical shaft for lowering said sand bag by swinging said lever, a latch for retaining said sand bag in lowered position, a spring within said post and connected with said lever for raising said sand bag when said latch is released and hydraulic means within said post to check the movement upwardly of said sand bag.

2. In a sand bag support, a base, a post extending upwardly therefrom, a sand bag, a vertical shaft connected with said sand bag, said post supporting said shaft for sliding movement, a lever pivoted to said post for lowering said sand bag, a latch for retaining said sand bag in lowered position, a spring within said post and connected with said lever for raising said sand bag when said latch is released and hydraulic means within said post to check the movement upwardly of said sand bag, said post constituting a reservoir for liquid for said hydraulic means.

3. In a sand bag support, a base, a post extending upwardly therefrom, a sand bag, a vertical shaft connected with said sand bag, said post supporting said shaft for sliding movement, a lever pivoted to said post for lowering said sand bag, a latch for retaining said sand bag in lowered position, a spring within said post and connected with said lever for raising said sand bag when said latch is released and hydraulic means within said post to check the movement upwardly of said sand bag, said hydraulic means comprising a cylinder stationary in said post, a plunger connected with said lever, liquid for said cylinder and plunger, a check valve permitting quick flow of the liquid into said cylinder when lowering said sand bag and a vent for permitting only restricted exit of said liquid from said cylinder upon release of said latch.

4. In a sand bag support, a base, a post extending upwardly therefrom, a sand bag, a vertical shaft connected with said sand bag, said post supporting said shaft for sliding movement, a lever pivoted to said post for lowering said sand bag, a latch for retaining said sand bag in lowered position, a spring within said post and connected with said lever for raising said sand bag when said latch is released and hydraulic means within said post to check the movement upwardly of said sand bag, said hydraulic means comprising a cylinder stationary in said post, a plunger connected with said lever, liquid for said cylinder and plunger, said post constituting a reservoir for such liquid, a check valve permitting quick flow of the liquid into said cylinder when lowering said sand bag and a vent for permitting only restricted exit of said liquid from said cylinder upon release of said latch.

5. In a sand bag structure, a frame including a hollow post, a sand bag supported for movement relative thereto, means tending to raise said sand bag, a handle provided for manually lowering said sand bag, a latch for retaining said sand bag in lowered position, a piston within said hollow post and operatively connected with said sand bag for movement simultaneously therewith, and fluid within said hollow post to check the movement of said piston and thereby said sand bag to raised position upon release of said latch, and vent means to permit relatively slow passage of said fluid past said piston.

6. In a sand bag structure, a sand bag, means tending to raise said sand bag, a handle provided for manually lowering said sand bag, a pivotally mounted latch for retaining said sand bag in lowered position and hydraulic means to check

the movement of said sand bag to raised position upon release of said latch, said latch including a latching surface formed on a radius from the pivotal axis of the latch to permit ease of manipulation of said latch against the action of said first means.

7. In a sand bag support, a base, a post extending upwardly therefrom, a sand bag, a vertical shaft connected with said sand bag, said 10 post supporting said shaft for sliding movement, a lever pivoted to said post for lowering said sand bag, a pivotally mounted latch for retaining said sand bag in lowered position, a spring with- in said post and connected with said lever for 15 raising said sand bag when said latch is released and hydraulic means within said post to check the movement upwardly of said sand bag, said latch including a latching surface formed on a radius from the pivotal axis of the latch to per- mit ease of manipulation of said latch against the action of said first means.

8. In a sand bag structure, a sand bag, means tending to raise said sand bag, a handle provided for manually lowering said sand bag, a 20 latch for retaining said sand bag in lowered po- 25 sition and hydraulic means to check the move-

ment of said sand bag to raised position upon release of said latch, said hydraulic means comprising a cylinder and a plunger, liquid for said cylinder and plunger, a check valve permitting quick flow of liquid into the cylinder when lowering said sand bag and a vent permitting restricted exit only of liquid from said cylinder upon release of said latch.

9. In a sand bag structure, a sand bag, means tending to raise said sand bag, a handle provided for manually lowering said sand bag, a pivotally mounted latch for retaining said sand bag in lowered position and hydraulic means to check the movement of said sand bag to raised position upon release of said latch, said hydraulic means comprising a cylinder and a plunger, liquid for said cylinder and plunger, a check valve permitting quick flow of liquid into the cylinder when lowering said sand bag and a vent permitting restricted exit only of liquid from said cylinder upon release of said latch, said latch including a latching surface formed on a radius from the pivotal axis of the latch to permit ease of manipulation of said latch against the action of said first means.
